Primary Examiner — Ian Simmons*Assistant Examiner* — Shannon Morgan(74) *Attorney, Agent, or Firm* — Robert Z. Evora, Esq.(57) **CLAIM**

The ornamental design for an infant cloth, as shown and described.

DESCRIPTION

FIG. 1 is a top perspective view of an infant cloth showing our new design;

FIG. 2 is a rear perspective view thereof;

FIG. 3 is a top plan view thereof;

FIG. 4 is a left side elevational view thereof;

FIG. 5 is a right side elevational view thereof;

FIG. 6 is a front elevational view thereof; the rear elevational view being an identical mirror image thereof; and, FIG. 7 is a bottom plan view thereof.

The broken lines shown in the drawings represent environmental structure in FIGS. 1-3 and 6-7 that form no part of the claimed design.
